(57) **CLAIM**

The ornamental design for a control panel for cooking appliance, as shown and described.

DESCRIPTION

FIG. 1 is a front elevation view of the control panel for cooking appliance; and,

FIG. 2 is a perspective view showing the control panel of FIG. 1 in the cooking appliance; the cooking appliance is shown in phantom lines and forms no part of the claimed design.

In both figures, the broken lines are provided for illustrative purposes only and form no part of the claimed design.

1 Claim, 2 Drawing Sheets

FIG. 1
